Specification for Design.

Patented Apr. 23, 1918.

Application filed February 18, 1918. Serial No. 217,999. Term of patent 7 years.

To all whom it may concern:

Be it known that I, JOSIAH D. GRUMMON, a citizen of the United States, residing in the borough of Manhattan, city of New York, county and State of New York, have invented a new, original, and ornamental Design for Spark-Plugs, of which the following is a specification, reference being had to the accompanying drawing, forming a part thereof, in which—

Figure 1 is a view in front elevation of a spark plug showing my new design.

Copies of this patent may be obtained for five cents each, by addressing the "Commissioner of Patents, Washington, D. C."

Fig. 2 is what may be considered a view in side elevation of the same spark plug.

Figs. 3 and 4 are bottom and top views respectively of the same spark plug shown in Figs. 1 and 2.

I claim—

The ornamental design for a spark plug as shown.

JOSIAH D. GRUMMON.

In the presence of—

P. M. RUSHMORE.
